BUTTON FASTENING DEVICE

Frank A. Holmgren, Minneapolis, Minn.

Application November 21, 1934, Serial No. 754,054

5 Claims. (Cl. 24—100.5)

This invention relates to a fastening or holding device and while the invention may have various applications, it particularly was designed to hold buttons on garments where the buttons must be frequently removed for the purpose of laundering the garment.

One class of the garments above referred to comprises coats worn by nurses, waitresses, factory workers and other persons and many of these persons are girls. The fasteners as now commonly used to hold on the buttons have sharp edges and corners and these often catch in the clothing of the girls and in silk hose worn by them, causing considerable damage.

15 It is an object of this invention to provide a fastening device for holding the button, which has a flat substantially smooth bottom, which is easily operated and which has no sharp points or burrs adapted to catch in the clothing.

20 It is a further object of the invention to provide a fastening device of simple, inexpensive and efficient construction, neat in appearance and which is very easily operated.

25 It is still another object of the invention to provide a fastening device having a base member having a smooth flat side, a second member slideable in said base member, said base member having a portion upturned on its upper side and having a slot therethrough and said second member having a portion upturned projecting through said slot, said two portions being adapted to engage to form a closed loop and being normally held in engagement by resilient means.

30 These and other objects and advantages of the invention will be fully set forth in the following description made in connection with the accompanying drawing, in which like reference characters refer to similar parts throughout the several views and in which:—

40 Fig. 1 is a view in side elevation showing the device as applied to a button;

Fig. 2 is a perspective view of the device;

Fig. 3 is a top plan view;

45 Fig. 4 is a vertical section taken on line 4—4 of Fig. 3;

Fig. 5 is a vertical section taken on line 5—5 of Fig. 4; and

50 Fig. 6 is a vertical section taken on line 6—6 of Fig. 3, said sections being taken as indicated by the arrows.

55 Referring to the drawing, the device comprises a main or base member designated generally as 10. Member 10 comprises a lower platelike portion 10a and an upper platelike portion 10b. Portion 10a has a substantially flat bottom surface and is of general rectangular form, the same having its side portions bent upwardly substantially at a right angle and then bent inwardly substantially at a right angle so that 60 slots or channels 10c are formed along the sides

thereof. Portion 10b has its side edge portions 10d bent downwardly substantially at a right angle and then bent outwardly substantially at a right angle so that said edge portions 10d are offset and in the assembly of member 10 said portions 10d are disposed in the slots 10c and clamped therein. A channel or passage 10e is thus formed in member 10, which passage is substantially rectangular in cross section. The portion 10b has a slot 10f extending longitudinally 10 therein adjacent its central portion and a tongue or member 10g upstands from member 10b at one end of said slot, said tongue preferably being formed of the metal removed from said slot. The upper end of member 10g is slightly curved 15 toward the rear end of member 10b. Member 10b in the rear of slot 10f has its central portion bent into semi-cylindrical form as shown at 10h. Member 10a has its rear portion also formed of slightly semi-cylindrical form opposite portion 10h as shown at 10i. A member 11 of platelike 20 form and substantially rectangular in shape slides in the passageway 10e and projects therefrom at the front end of member 10. Member 11 has a bill or portion 11a upstanding therefrom, the same projecting through slot 10f and said portion or member 11a has its upper portion bent into a substantially semi-cylindrical curve extending forwardly, the forward end of which normally contacts with the upper curved end of 25 member 10g. Member 10a has its rear end bent upwardly to form a closure for channel 10e and for the substantially cylindrical enlargement at the rear end of said channel formed by the opposed semi-cylindrical portions 10h and 10i. A 30 coiled compression spring 12 is disposed in said substantially cylindrical passage formed by portions 10i and 10h, one end of which bears against the end of said passage and the other end of which is engaged by the rear end of member 11. 35

With the described structure the device normally occupies the position shown in Fig. 2. Spring 12 engaging the rear end of member 11 moves the same forwardly until the upper end of member 11a engages the upper end of member 10g. Members 10g and 11a thus coact to form a closed loop. When the device is to be attached to or removed from a button, member 11 is pressed upon by one finger and the end of member 10 engaged by the thumb or another finger. Member 11 is pushed into member 10 against the tension of spring 12 and member 11a is thus moved away from member 10g forming an opening or passage between said members as shown in Fig. 1. The eye or loop B1 of the button B can then be passed under the hook of member 11a or said hook may be passed through the eye or loop B1. The member 11 is then released and member 11a moves into engagement with member 10g and the eye or loop B1 is firmly retained 50

between members 10g and 11a. The eyelet B1 is passed through a hole made for it in the garment and when the member 10 is attached to said eyelet the button is secured to the garment. It can be readily removed when the garment is to be laundered by detaching member 10 as above described. The bottom of member 10 it will be noted is flat and substantially plain and both this member and member 11 are free from any sharp corners, edges or burrs which tend to catch on the clothing and particularly on silk hose. At the same time the device is very easily manipulated and can be quickly removed from the button and quickly engaged with the button.

From the above description it is seen that applicant has provided a very simple and efficient fastening device for holding buttons and one which eliminates serious objections to the devices previously used. The present device is simple, easily made, very efficient and can be easily and quickly operated. The device will, of course, be made of material which will not easily corrode or it may be plated with non-corrosive material. The same has been amply demonstrated in actual practice and found to be very successful and efficient.

It will, of course, be understood that various changes may be made in the form, details, arrangement and proportions of the parts, without departing from the scope of applicant's invention, which generally stated, consists in a device capable of carrying out the objects above set forth in the parts and combinations of parts disclosed and defined in the appended claims.

What is claimed is:—

1. A device for fastening to a garment a button having an apertured shank adapted to pass through an aperture in said garment having in combination, a member having a flat substantially plane and smooth bottom surface and being of small thickness relatively to the length of said shank and having a passage extending longitudinally therethrough forming a guide channel, a second thin platelike member slidable in and guided in said passage, a member upstanding from said first mentioned member, another member upstanding from said second mentioned member, said last two members being normally in engagement and forming a closed loop and resilient means disposed in said first mentioned member and engaging said second mentioned member to hold said last two mentioned members in engagement with said loop closed, said second mentioned member projecting at one end of said first mentioned member and adapted to be moved against the said resilient means for relatively moving said last two members to open said loop.

2. A device for fastening to a garment a button having an apertured shank adapted to pass through an aperture in said garment having in combination, a member having a flat substantially plane and smooth bottom portion and being of small thickness relatively to the length of said shank and having a passage therethrough forming a guide channel, a second thin plate-like member slidable in and guided in said passage, a third member upstanding from said first mentioned member, said first mentioned member having a slot therein extending longitudinally thereof from said last mentioned member, a fourth member carried by said second mentioned member and extending upwardly through said slot, said third and fourth members being normally in engagement and one of them being bent toward the other so that they form a closed loop and a spring en-

gaging said second mentioned member and adapted to hold said third and fourth members in engagement, said second member projecting from one end of said first mentioned member and being movable against the tension of said spring for relatively moving said third and fourth members to open said loop.

3. A fastening device having in combination, a comparatively thin member having a flat substantially smooth bottom portion, said member having a longitudinal passage therein, a second thin platelike member slidable and guided in said passage, said first mentioned member having a slot formed in its top portion, a tongue struck up from said member at one end of said slot, said second member having a portion struck up therefrom extending vertically through said slot, the same having its terminal portion engaging said tongue, a spring disposed in said first mentioned member engaging one end thereof and engaging the end of said second mentioned member so that said portion of said second mentioned member is held in engagement with said tongue, said second mentioned member being movable against said spring to move said portion away from said tongue.

4. A fastening device comprising a platelike member of general rectangular form having a substantially smooth flat surface and having its longitudinal edges reversely bent to form channels, a second platelike member of similar form having its longitudinal edge portions offset and received and held in said channels whereby a passage of rectangular form in cross section is formed between said members, said second member having a slot formed in its upper side extending longitudinally thereof, a tongue struck up from said slot and upstanding from said second member at one end of said slot, a third platelike member received in said passage and having a portion struck up and upstanding therefrom and extending through said slot, said portion and tongue being adapted to engage to form a closed loop and a spring disposed in one end of said passage engaging one end of said third member to hold said portion and tongue in engagement, said third member projecting at one end of said passage so as to be pressed upon against the tension of said spring to relatively move said tongue and portion to open said loop.

5. A device for fastening to a garment a button having an apertured shank adapted to pass through an aperture in said garment having in combination, a plate-like member having a flat, plane and smooth bottom surface and being of small thickness relatively to the length of said shank and having a passage extending longitudinally therethrough forming a guide channel, a second thin plate-like member slidable in and guided in said passage, a member upstanding from the top of said first mentioned member, another member upstanding from said second member, said last two members being normally in engagement and forming a closed loop and resilient means disposed in said first mentioned member and engaging said second mentioned member to hold said last two mentioned members in engagement with said loop closed, said second mentioned member having a part projecting from said first mentioned member and adapted to be moved against said resilient means for relatively moving said last two mentioned members to open said loop.
